CLAIM

The ornamental design for syringe housing of a syringe injection safety device, as shown and described.

DESCRIPTION

FIG. 1 is a top and front perspective view of a syringe housing of a syringe injection safety device in accordance with a first embodiment of our new design;

FIG. 2 is a top and left side perspective view thereof;

FIG. 3 is a top and rear perspective view thereof;

FIG. 4 is a front elevational view thereof and a rear elevational view being identical;

FIG. 5 is a left side elevational view thereof and a right side elevational view being identical;

FIG. 6 is a top plan view thereof;

FIG. 7 is a bottom plan view thereof;

FIG. 8 is an enlarged fragmentary view of a portion of the syringe housing shown in FIGS. 2 and 3;

FIG. 9 is an enlarged fragmentary view of a portion of the syringe housing shown in FIG. 4;

FIG. 10 is a front elevational view of a syringe housing of a syringe injection safety device in accordance with a second embodiment of our new design;

FIG. 11 is a rear elevational view of FIG. 10;

FIG. 12 is a left side elevational view of FIG. 10;

FIG. 13 is a right side elevational view of FIG. 10;

FIG. 14 is a top plan view of FIG. 10;

FIG. 15 is a bottom plan view of FIG. 10;

FIG. 16 is an enlarged fragmentary view of a portion of the syringe housing shown in FIG. 11;

FIG. 17 is an enlarged fragmentary view of a portion of the syringe housing shown in FIG. 12; and,

(Continued)

FIG. 18 is an enlarged perspective fragmentary view the portion of the syringe housing shown in FIGS. 16 and 17. The broken lines in the drawings illustrate portions of the syringe housing of a syringe injection safety device and form no part of the claimed design.
